UNITED STATES PATENT OFFICE.

DAVID DUNBAR, OF GLASGOW, SCOTLAND, ASSIGNOR TO THE LENNOX MANUFACTURING COMPANY, LIMITED, OF DUNTOCHER, DUMBARTONSHIRE, SCOTLAND.

TIE FOR MASONRY.

Application filed November 26, 1919. Serial No. 340,744.

To all whom it may concern:

Be it known that I, DAVID DUNBAR, a subject of the King of Great Britain and Ireland and the Isle of Man, and a resident of Glasgow, Scotland, engineer and master of works, have invented new and useful Improvements in Ties for Masonry, of which the following is a specification.

This invention has reference to improvements in and relating to holdfast devices for retaining wooden straps, laths and the like in dwelling houses, and other brickwork, stonework, concrete and like structures.

According to my improvements the holdfast devices would consist of galvanized sheet metal or the like, and be of a U channel, or like formation outside the line of brickwork or the like to enclose and hold the wooden strap, lath or the like; while it would have an inwardly radial or projecting arm or arms, or split arms to fit over and be embedded in the brickwork or the like.

These radial arms would preferably be formed of a vertical side and top horizontal formation, or vice versa, next the projecting out holding part for the woodwork beyond the brick or like wall, and be embedded between the courses of the "stretchers" and "headers" of the brickwork or like structure.

These holdfast devices can be embedded between the series of bricks or the like at any spaced distances apart, and be placed either horizontally or vertically. And in order that my said invention and the manner of carrying the same into effect or practice may be properly understood I have hereunto appended three sheets of explanatory drawings in which the same reference letters are used to indicate corresponding parts in all the figures where shown.

Figure 1 on Sheet 1 shows a view of a holdfast construction according to my invention for holding one wooden strap, lath or the like.

Figure 2 shows the same construction for holding two wooden laths.

Figure 3 is a transverse section as taken on the line 3—3 of Figure 1, and 3—3 of Figure 2.

Figures 4 and 5 are similar views to Figure 1 but showing the channel shaped holder inverted for carrying the strap or the like, and the radial arms slightly modified.

While Figure 6 is a transverse section as

taken on the lines 6—6 of Figure 4 or 6—6 of Figure 5.

Figures 6^a and 6^b Sheet 2, show modified forms of radial arms suitable for a holdfast device as illustrated in Figures 1, 4 60 and 5.

Figure 7 on Sheet 2 represents a vertical section of an external wall of brick or like construction showing the practical application of the modification of holdfast shown in Figure 1; and Figure 8 on same sheet shows a like view of holdfast corresponding to Figure 2 on Sheet 1.

Figure 9 on Sheet 3 shows a perspective view of the practical application of the holdfast shown on Figure 5, while Figure 10 on same sheet shows a horizontal section showing the practical application of the modification of holdfast shown in Figure 4 of Sheet 1.

Referring to these drawings—

As shown in Figure 1 the holdfast devices consist of a metal U channel or like formed part A outside the line of brickwork or other material forming the wall or building to enclose and hold the wooden strap, lath or the like, and the radial arm B which may be split or divided as shown in Figures 6^a or 6^b is arranged to fit over and be embedded in the brickwork or other material, the device being formed with a twist at B².

In Figure 1 the end B¹ of the arm B, which is shown broken away is formed of a knee or like shape to grip the side of the wall.

In Figure 6^b this end B¹ is shown split.

In the arrangement shown at Figure 6^a the end of the arm B remote from the part A is split into projecting arms or it may be otherwise made of a broader cross section than the arm B. By this means it is not necessary that this end should project beyond the brickwork or, the like as the broadened end prevents the longitudinal displacement of the device.

A vertical web C is formed on the arm B to be placed in the joints and abut against the material forming the wall.

In Figure 2 the radial arm B is shown as formed with the web C and as having channel shaped holder pockets A' on each end to carry the straps, laths or the like.

In Figures 4 and 5 the holder channel A is shown as inverted to carry the straps, laths or the like when these are arranged 110

2
vertically, and the radial arm B is shown as partially turned over flat horizontally with a flange at D which is equivalent to the web C shown in Figures 1 and 2, while 5 in Figure 5 the arm is given a twisted formation at B². But in any these modifications the channels A can be arranged to be set either vertically or horizontally by simply inverting or reversing or setting at right 10 angles and either to right or left the position of the channels A to suit the position of the wooden straps or the like.

Instead of forming the part A of channel shape the outside limb of same may be dispensed with and the wooden strap E be attached to the inner limb by bolts, screws or like devices.

Figures 7 and 8 are vertical sections of the wall F of a building wherein the constructions of holders illustrated in Figures 1 and 20 2 are respectively shown to practical application. In these cases the holdfasts A are shown as carrying the wooden straps E embedded in the plaster G and the arms B as 25 passing through the brickwork F, above the floor H and cove skirting I.

In Figure 9 the application of the modification of holder illustrated in Figure 5 is shown as applied in an analogous manner 30 to that shown in Figures 7 and 8 but with a structure having a hollow wall. While in Figure 10 is illustrated the application of the modification shown in Figure 4 to a solid wall. All these modifications are such 35 that the holdfast and radial arms are tied to the brick or stonework and rendered immovable.

By these constructions as particularly 40 illustrated in Figures 1 to 6 an air cushion is formed at a between the inner surface or inner limb or part of holdfast forming the channel A for carrying the woodwork E and also at b between the outer surface of 45 said channel A and the brickwork or equivalent material F of which the building is constructed.

What I claim as my invention is:—

1. A holdfast device comprising an arm adapted to be embedded in the brickwork,

stonework and the like, means at one end 50 thereof for preventing longitudinal displacement of the device, and a channel portion at the other end thereof adapted to retain a wooden strap, lath and the like in position, said channel portion being bent to bear on the face of the wall and again bent to form an air space between the wall and the said wooden strap, lath and the like.

2. A holdfast device comprising an arm adapted to be embedded in the brickwork, 60 stonework and the like, and a channel formation at each end thereof adapted to retain a wooden strap, lath or the like in position and to prevent longitudinal displacement of the device, said channel portions 65 being bent to bear on the face of the wall and again bent to form an air space between the wall and the said wooden strap, lath and the like supported thereby.

3. A holdfast device comprising an arm 70 adapted to be embedded in the brickwork, stonework and the like, a flange extending longitudinally thereof, means at one end of the said arm for preventing longitudinal displacement of the device, and a channel 75 portion at the other end thereof adapted to retain a wooden strap, lath and the like in position, said channel portion being bent to bear on the face of the wall and again bent to form an air space between the wall and the said wooden strap, lath and the like.

4. A holdfast device comprising an arm adapted to be embedded in the brickwork, 80 stonework and the like, a flange extending longitudinally thereof, and a channel formation at each end of said arm adapted to retain a wooden strap, lath and the like in position and to prevent longitudinal displacement of the device, said channel 85 portions being bent to bear on the face of the wall and again bent to form an air space between the wall and the said wooden strap, lath and the like supported thereby.

DAVID DUNBAR.
